UNITED STATES PATENT OFFICE

FRANK D. MARTIN, OF CHICAGO, ILLINOIS, ASSIGNOR TO WESTERN ELECTRIC COMPANY, INCORPORATED, OF NEW YORK, N. Y., A CORPORATION OF NEW YORK

APPARATUS FOR HANDLING MATERIAL

Application filed December 26, 1929. Serial No. 416,342.

This invention relates to apparatus for handling material, and more particularly to apparatus for supplying rod to a wire drawing machine.

Objects of the invention are to provide a simple and efficient apparatus for handling strand material and for supplying a continuous length thereof.

One embodiment of the invention contemplates the provision of an apparatus for supplying copper rod to a wire drawing machine, wherein an enclosure or housing is provided adjacent to the wire drawing compartment and communicating therewith, in which the rod is placed during the operation of the wire drawing machine. Several coils of the rod are interwelded and placed in stacks upon two vertical posts mounted on the upper surface of a wheeled platform. One end of the rod on one post is welded to an end of the rod on the other post with a suitable amount of slack therebetween, and one free end of the coil is then strung in the usual manner with the wire drawing dies. The loaded platform is carried by a crane to the vicinity of the housing, which is then opened and the platform wheeled into place within the housing. The free end of the rod having the dies thereon is passed over a rotatable drum suspended from the roof of the housing, and then fed into the wire drawing compartment wherein it is strung in the usual manner. The interconnecting portion of the rod between the two posts is looped over another similar drum so that upon exhaustion of the rod upon the first post, the rod on the second post is ready to be drawn without stopping the operation of the wire drawing machine. On approaching the end of the supply, another loaded platform may be carried by the crane to the vicinity of the supply housing and the rod thereon welded to the remaining supply, after which the empty platform can be removed and the loaded platform substituted so that the operation of the wire drawing machine may be continued without re-stringing.

It is believed that the invention will be clearly understood from the following detailed description of a preferred embodiment

thereof, reference being had to the accompanying drawings, wherein

Fig. 1 is an elevational view, partly in section, of a wire drawing machine having associated therewith a rod supplying apparatus embodying the invention;

Fig. 2 is a vertical section on line 2—2 of Fig. 1;

Fig. 3 is a fragmentary plan view, partly in section on line 3—3 of Fig. 1.

Referring now to the drawings wherein like reference numerals designate corresponding parts throughout the several views, it will be observed that a wire drawing machine is shown somewhat schematically in Fig. 1 and comprises a wire drawing compartment 10 and a take-up compartment 11, both mounted upon a common supporting base 12 embedded in a foundation or floor 13. A pair of stepped wire drawing capstans 15—15 and cooperating idler sheaves 16—16 are mounted within the wire drawing compartment 11 with suitable brackets 17—17 interposed therebetween for supporting the reducing dies in the usual manner. An opening 18 is provided in the front side of the wire drawing compartment for facilitating the threading of the rod and the reducing dies before starting the operation of the machine. A suitable door (not shown) is provided for closing the opening 18 during the operation of the wire drawing mechanism.

In accordance with a feature of the present invention, a supply compartment or housing 20 is provided adjacent to the wire drawing compartment 10 for enclosing a supply of the rod to be drawn. The supply compartment 20 consists of oppositely disposed side walls 21—21, a roof 22, and a rear wall 23 which are rigidly braced and secured together by means of angle beams as shown in drawings. On the front side of the compartment 20 there is provided a door 25, preferably of a rollable type, having a handle 26 whereby it may be manually raised or lowered. When raised, the door 25 automatically rolls around a drum 27 mounted near the roof of the compartment (Fig. 2).

A pair of flanged drums 30 and 31 are rotatably supported in U-shaped brackets

32—32 depending from the roof of the compartment 20. One side of the brackets 32 is formed with an upwardly extending portion 33 (Fig. 2) for attachment to an angle iron framework 34 (Fig. 3) secured to the under side of the roof.

The rod to be drawn is placed in coil form upon a pair of vertical posts 35 and 36 mounted upon a rollable support or wheeled platform 37. If several coils are placed on a post the inner end of each coil is welded to the outer end of the adjacent coil on that post. Guard flanges 38—38 are provided at the upper ends of the posts 35 and 36 for preventing tangling 10 or snarling of the rod as it is withdrawn from the posts. An eye-bolt or hook 39 is attached to each corner of the platform 37 by means of which the platform may be lifted by a suitable crane (not shown) and carried to and from 15 the vicinity of the supply compartment 20.

After placing a coil of rod upon each of the posts 35 and 36, the inner end of the rod on the post 35 is welded to the outer end of the rod on the post 36. The outer end of the rod on 20 the post 35 is then strung with the reducing dies in the usual manner, after which the platform is carried by a crane to the vicinity of the supply compartment 20. The platform is then wheeled into position within the compartment 20, as shown in the drawings. The portion of the rod interconnecting the coils on the two posts is now threaded over the take-off drum 31 and the outer or free end of the rod 25 having the dies strung thereon is threaded over the take-off drum 30 and then through an opening (not shown) in the side wall of the compartment 20 and into the wire drawing compartment 10, wherein it is threaded in the usual manner around the capstans 15 30 and the associated idler sheaves 16, the reducing dies being located in their supporting brackets 17. The end of the rod is then passed from the wire drawing compartment 10 into the take-up compartment 11, wherein 35 it is threaded under an idler sheave 42, over a similar sheave 43, through a distributor 44, and then around a take-up reel 45. The doors 40 of the supply and wire drawing compartments, and also a door 47 on the front side of the take-up compartment are now closed and 45 the apparatus is ready for operation.

Upon approaching the end of the supply of rod on the second post 36, another loaded platform is carried by a crane to the vicinity 50 of the supply compartment 20, the wire drawing operation is temporarily stopped, the door 25 of the supply compartment is opened and the end of the remaining rod is welded to an end of the rod on the loaded platform, after 55 which the empty platform is wheeled out of the compartment through an opening 48 in the rear wall thereof and the loaded platform is wheeled into the compartment. Thus, 60 since the restringing of the die and the re-threading of the rod through the wire draw-

ing mechanism is eliminated, the wire drawing operation may quickly be resumed.

It is believed that the advantages of the invention will be clearly apparent from the above description. By enclosing the rod supply within the compartment as described above, the operator is adequately protected against any possible injury which may be due to tangling, snarling or breaking of the rod as it is drawn from the supply. Also, by supporting the supply upon a wheeled platform adapted to be hoisted and transported mechanically, the rod may be handled conveniently and in large quantities with a minimum amount of manual labor.

Although the embodiment of the invention herein illustrated and described is particularly applicable to wire drawing apparatus, it should be understood that the invention is capable of other applications within the scope 85 of the appended claims.

What is claimed is:

1. In an apparatus for handling strand material, a support, a plurality of upright members extending from the support, a supply of strand material in coil form mounted upon each of the upright members, the strand supplies being interconnected so as to permit an uninterrupted feed of the strand from the supplies seriatim, and a rotatable drum positioned above each of the supplies for facilitating the withdrawal of the strand from the associated supply.

2. In an apparatus for handling strand material, a rollable support, a plurality of strand supplies mounted upon the support, the inner end of one of the supplies being connected to the outer end of another of the supplies, an enclosure for accommodating the support with the supplies thereon, and rotatable means individual to each of the supplies and mounted within the enclosure for facilitating the withdrawal of the strand material from the respective supplies, said supplies and rotatable means being arranged so as to permit an uninterrupted feed of material from the supplies seriatim.

3. In an apparatus for supplying strand material, a wheeled platform, a plurality of vertical posts attached to the platform, a supply of strand material in coil form mounted upon each post, a housing for enclosing the supplies, and rotatable means individual to each of the supplies and mounted within the housing for facilitating the withdrawal of the strand material from the respective supplies.

4. In an apparatus for supplying strand material, a wheeled platform, means mounted upon the platform for holding a plurality of strand supplies in coil form with one end of a strand of one of the supplies connected to one end of a strand of another supply, a housing for enclosing the wheeled platform with the supplies mounted thereon, the housing having

an opening therein for the passage of the platform into and out of the housing, a door for closing the opening, and a rotatable member associated with each of the supplies for facilitating the withdrawal of the strands from the respective supplies, the rotatable members being constructed and arranged so as to permit an uninterrupted feed of the strands from the supplies seriatim.

10 In witness whereof, I hereunto subscribe my name this 12th day of December, A. D. 1929.

FRANK D. MARTIN.
